RAILWAY CAR

Rolf Mowatt-Larsen, Bridgeon, Mo., assignor to ACF Industries, Incorporated, New York, N.Y., a corporation of New Jersey

Filed Jan. 16, 1964, Ser. No. 338,072
4 Claims. (Cl. 105—368)

This invention relates to railway cars for transporting highway trailers and more particularly to an improved side sill structure for such railway cars.

In railway flat cars of a so-called low level type for transporting highway trailers, the floor or deck of the railway car is positioned at as low an elevation as possible in order to provide the necessary overhead clearance for the highway trailers through tunnels and the like where limiting overhead clearances are encountered. It is desirable to have means along the sides of the flat car to position and guide the roadway wheels of the trailers as they are driven onto the car. For this purpose the side sill structure on each side of the car extends above the elevation of the deck and acts to strengthen the underframe as well as to guide the roadway wheels. The present invention constitutes an improvement on the side sill structure for each side of the railway car.

An object of the present invention is the provision of a low level flat car for carrying highway trailers and the like in which the roadway wheels of a trailer are guided along the sides of a railway car to position the trailer properly on the railway car.

A further object of this invention is to provide a side sill structure for each side of a low level flat car for carrying trailers and the like which car is light weight in construction and economical to manufacture.

An additional object of the invention is the provision of a side sill structure for each side of a low level flat car which reinforces the underframe against flexure while guiding the roadway wheels of highway vehicles to center the vehicles on the trailer.

The above objects are accomplished by the provision of a railway flat car having a side sill structure on each side of the flat car underframe extending substantially the length of the car, each side sill structure having a web with an upper portion extending above the level of the floor plate; and a rub rail structure on the inner surface of the web comprising a lower leg or flange extending over the floor plate, an upper flange secured to the web and extending in a generally parallel relation to the lower frame, and a plate extending between and connecting the flanges for forming a rub rail against which the tires of a roadway vehicle may rub and be guided as trailers move along the railway car. Other objects and features will be in part apparent and in part pointed out hereinafter.

The invention accordingly comprises the constructions hereinafter described, the scope of the invention being indicated in the following claims.

In the accompanying drawings, in which several or various possible embodiments of the invention are illustrated,

FIGURE 1 is a perspective view of a railway flat car embodying the present invention adapted to transport trailers;

FIGURE 2 is a partial section taken generally along line 2—2 of FIGURE 1;

FIGURE 3 is a fragmentary side view of one end of a side sill structure of the flat car shown in FIGURE 1;

FIGURE 4 is a top plan of the side sill structure shown in FIGURE 3;

FIGURE 5 is a section taken generally along line 5—5 of FIGURE 3;

FIGURE 6 is an enlarged plan of a modification of my

2

invention in which the sections forming the rub rail structure are not rigidly connected to each other;

FIGURE 7 is a partial section of a modification of the present invention in which the side sill structure embodies a generally channel-shaped side sill; and

FIGURE 8 is a partial section of a further modification similar to the embodiment of FIGURE 7 and showing the side sill structure extending in a vertical direction.

Corresponding reference characters indicate corresponding parts throughout the several views of the drawings.

Referring to FIGURE 1, a railway flat car generally designated 10 has wheel trucks 12 at each end thereof and is adapted to transport a pair of trailer (not shown). Collapsible trailer hitches H are shown in collapsed position on flat car 10 and when erected are adapted to secure the trailers on the flat car.

The underframe of railway car 10 comprises a center sill generally designated 14 extending longitudinally along each side of the car, each having a vertical web 16 and a bottom cover plate 18. A plurality of transverse members or crossbearers 22 extend between center sills 14 and each is formed of a channel iron having upper and lower flanges 24. Cantilevered on web 16 of each center sill 14 is a plurality of stub crossbearers 26. Each stub crossbearer has a vertical web 28. Extending around the free edges of vertical web 28 is a continuous flange 30.

Forming the upper cover plate of center sill 14 is a floor or deck plate designated generally 32 and having a portion cutout to form an intermediate opening 26. A Z member 34 extends around intermediate opening 36 and reinforces the adjacent edge of deck plate 32. The lower flange of Z member 34 is supported on crossbearers 22. For further details of flat car 10, reference is made to co-pending application Serial No. 293,092, filed July 5, 1953, and entitled "Railway Car," the entire disclosure of which is incorporated by this reference.

The improved side sill structure which constitutes my invention is indicated generally at 38 and includes a vertical web 40 adjacent each side edge of deck plate 32 and extending upwardly therefrom. An inturned bottom base member 42 is integral with web 40 and has an upturned flange 44 engaging the underside of deck plate 32. Web 40 has an upper outwardly sloping portion 46. Mounted on the upper edge of portion 46 is a tubular head 48 which extends the length of car 10.

Mounted on the inner surface of tubular head 48 and web 40 is a rub rail structure generally designated 50 and being generally channel-shaped in cross section. Lower leg or flange 52 of rub rail structure 50 is secured, such as by welding, along its outer edge to web 40, and upper leg or flange 54 is secured, such as by welding, along its outer edge to tubular member 48. Connecting legs 52 and 54 is a connecting plate or web 56 formed integrally with legs 52 and 54 thereby to provide a generally channel-shaped rub rail structure 50. A tire or wheel of a trailer is indicated at W and rubs against or contacts rub rail structure 50 if the trailer is not properly centered on railway car 10.

Referring to FIGURES 3—5, rub rail structure 50 is formed in a plurality of longitudinally extending intermediate sections 57 and end sections 58 which are mounted on each side sill structure 38. The ends of adjacent sections 57 and 58 are preferably butt welded to each other along seams 59 to form a continuous rub rail structure 50 whereby the rub rail functions as an integral structure under loading conditions and flexure.

To guide the tire W as a trailer or tractor is being driven onto flat car 10, each end section 58 is tapered to merge gradually with vertical web 40 and tubular member 48 of the side sill structure. Tapered upper and lower legs 52a and 54a of each section 58 are integrally connected by plate 56a. Forming the outer free end of

plate 56a is a tapered end portion 62 merging into tubular member 48 and web 40. As a tractor or trailer first reaches the end of flat car 10 and is not centered properly, the tire will first rub against or contact tapered end section 58 and be guided thereby onto intermediate rub rail section 57.

Openings 68 may be spaced along the length of leg 54 to permit welding of leg 52 to web 40 from inside rub rail structure 50 and to allow painting the inside of the rub rail structure, if desired. In addition, openings 68 decrease the weight of the rub rail structure. As openings 68 permit the entry of water and other foreign matter, it is desirable to have openings 69 spaced along flange 52 and staggered with respect to openings 68 in flange 54. The welds in rub rail structure 50 are disposed preferably along the upper corners of legs 52 and 54. As the force exerted by the tires W is generally parallel to legs 52 and 54, the welds are primarily for the holding of rub rail structure 50 in position as only a relatively small portion of the force exerted by tires W is transmitted to the welds. The welds along legs 52 and 54 may be intermittent or spaced longitudinally since subjected only to a relatively small portion of the force exerted by tires W.

In the loaded flat car 10, maximum tension is along the upper portion of side sill structure 38. Rub rail structure 50 being positioned adjacent the upper edge of side sill structure 38 strengthens and stiffens side sill structure 50 against flexure from loading and impact forces. Thus, rub rail structure 50 as illustrated in the embodiment of FIGURES 1-5 acts both as a stiffener and a guide member.

Referring to FIGURE 6, an embodiment of the invention is illustrated in which the sections comprising the rub rail structure 50 are not tightly connected to each other. The side sill structure normally is of sufficient strength to adequately resist bending or flexure without the increased stiffness afforded by the rub rail structure. Each end of intermediate section 57 and the inner end of each section 58 has an outwardly bent portion 70 extending beyond the adjacent flanges 52, 54 and 52a, 54a respectively. Adjacent bent portions 70 are not secured to each other thereby permitting rub rail structure 50 to be easily secured to side sill structure 38, such as by welding. This permits a relatively simple securing of rub rail structure 50 to side sill structure 38 as adjacent sections 57, 58 do not require securing to each other thereby requiring only a minimum of time for fabrication. It is to be understood that rub rail structure 50 may be bolted to side sill structure 38 in the event it is desired to have a removable rub rail.

Referring to FIGURE 7, a modification of the side sill structure is indicated by numeral 38b and includes a channel-shaped web member 40b extending upwardly alongside floor plate 32. Crossbearer 22b extends from member 40b to a center sill (not shown). A brace or stiffener 72 extends between crossbearer 22b and the center sill. Rub rail structure 50b is channel-shaped and has legs 52b and 54b welded to the inner surface of channel 40b. Web 56b connects legs 52b and 54b. Web members 40b and 56b are tilted slightly with respect to the vertical direction.

Referring to FIGURE 8, another embodiment of the side sill structure is indicated in which channel members 38b and 50b have webs 40b and 56b respectively which extend in a vertical direction. A greater contact of rub rail structure 50b with tire W is provided in the embodiment of FIGURE 8 when the tire rubs against the rub rail. It is to be understood that the rub rail structure may extend at any desired angle with respect to a vertical direction and that the side sill structure 38 may be of any desired shape, such as an S or Z shape, for example.

In view of foregoing, it will be seen that the several objects of the invention are achieved and other advantageous results obtained.

As various changes could be made in the above construction without departing from the scope of the invention, it is intended that all matter contained in the above description or shown in the accompanying drawings shall be interpreted as illustrative and not in a limiting sense.

What is claimed is:

1. In a railway flat car adapted to transport highway trailers, an underframe comprising a center sill structure extending substantially the length of the underframe, a plurality of crossbearer members spaced along the length of the center sill structure and extending laterally therefrom, a side sill structure on each side of the center sill structure supported on the adjacent crossbearer members, a generally flat deck plate adjacent each side sill structure and disposed at a level below the upper surface of the side sill structure and adapted to support the roadway wheels of highway trailers, each of the side sill structures comprising a side sill web disposed adjacent the side edge of the adjacent deck plate and having an upper portion extending above the level of the deck plate, and an integral generally channel-shaped rub rail structure on the inner surface of each side sill web forming with the side sill web a box-shaped structure spaced from the deck plate, each channel-shaped rub rail structure comprising a lower leg welded to the upper portion of the associated side sill web at a position above the deck plate and extending in a generally lateral direction over the deck plate in generally parallel, spaced relation thereto, an upper leg welded to the upper portion of the associated side sill web in spaced parallel relation to the lower leg, and an integral connecting plate spaced inwardly from the side sill and extending between the upper and lower legs adapted to contact and guide the tires of a highway trailer on the railway car.
2. In a railway flat car for carrying roadway vehicles having an underframe with a center sill structure extending substantially the length of the underframe, a plurality of transverse members spaced along the length of the center sill structure, and a generally flat deck plate adapted to support the wheels of roadway vehicles, the improvement comprising a side sill structure on each side of the center sill structure each having a side sill web disposed adjacent the side edge of the adjacent deck plate and having an upper portion extending above the level of the deck plate, and a separate integral rub rail structure generally channel-shaped in cross section secured to the inner surface of each side sill web, the integral rub rail structures each having upper and lower flanges extending over the deck plate in a generally horizontal direction and connected by an integral main body plate spaced inwardly from the side sill web, whereby roadway vehicles carried on the railway car are guided and centered on the railway car by said rub rail structures, the lower flange being spaced above the deck plate and extending in a generally lateral direction over the deck plate in generally parallel spaced relation thereto and being welded to the inner surface of said side sill web, said rub rail structures each being tapered inwardly from each end of the car and merging gradually with the respective side sill web whereby the span between the rub rail structures at each end of the railway car is greater than the span between the rub rail structures intermediate the length of the railway car so that trailers or the like are centered on the railway car upon contact with the tapered ends of the rub rail structures; each rub rail structure comprising a plurality of longitudinally extending sections aligned with each other and spaced slightly from each other, the end of each section having its body plate extending beyond its upper and lower flanges with the extending portion of each body plate turned outwardly toward the adjacent side sill to face the adjacent section while spaced slightly therefrom.
3. In a railway flat car as set forth in claim 2, said

side sill structures each comprising a tubular head on the respective extending side sill web to reinforce the side sill structure against bending.

4. In a railway flat car adapted to transport highway trailers, an underframe comprising a center sill structure extending substantially the length of the underframe, a plurality of crossbearer members spaced along the length of the center sill structure and extending laterally therefrom, a side sill structure on each side of the center sill structure supported on the adjacent crossbearer members, a generally flat deck plate adjacent each side sill structure and disposed at a level below the upper surface of the side sill structure and adapted to support the roadway wheels of highway trailers, each side sill structure comprising a generally channel-shaped base secured to the adjacent crossbearer members beneath the deck plate and an integral upwardly directed web extending alongside and above the deck plate, said deck plate extending over the generally channel-shaped base in a generally parallel relation to the web of the base and forming with the base a box-shaped section, and an integral generally channel-shaped rub rail structure on the inner surface of each side sill web forming a box-shaped structure spaced from the deck plate, each channel-

shaped rub rail structure comprising a lower leg welded to the upper portion of the associated side sill web at a position above the deck plate and extending in a generally lateral direction over the deck plate in generally parallel spaced relation thereto, an upper leg welded to the upper portion of the associated side sill web in spaced parallel relation to the lower leg, and an integral connecting plate spaced inwardly from the side sill and extending between the upper and lower legs adapted to contact and guide the tires of a highway trailer on the railway car.
